LIFTING SLING FOR CONTAINERS

Frederick K. Fildes, Altoona, Pa.

Application July 28, 1933, Serial No. 682,635

4 Claims. (Cl. 294—67)

This invention relates to apparatus for transferring and handling shipping containers or the like, and more specifically to lifting slings for this purpose which are controlled by an operator standing on the ground alongside the body to be lifted.

Railway shipping containers are customarily disposed in rows on the floor of a freight car, and to position them properly requires a hoisting apparatus having provision for raising, lowering and shifting a container in a truly vertical position, square with respect to the container seats on the floor of the car. To accomplish this, slings have been developed with load engaging means at the four corners, and the containers have been equipped with suspension hooks or like devices at their top corners.

With certain of the lifting slings heretofore used, it is necessary that a workman ride the sling and make the coupling adjustments from the top of the container, and this is a hazardous time-consuming operation. Other lifting slings in which the coupling with containers is effected automatically are characterized by elaborate and expensive construction.

Accordingly the principal object of my invention is to provide a lifting sling of extremely simple and economical construction which may be coupled to the container to be transferred without the services of a man at the top of the container.

A further object of the invention is to provide a lifting sling which may be operated from a position alongside the container at either side thereof, or at either side of the car upon which it is seated.

Other objects and advantages of the invention will be apparent from the detailed description of a preferred embodiment thereof which follows, having reference to the accompanying drawings, whereof:

Fig. I is a side view of hoisting apparatus including a lifting sling of my invention shown in engagement with a container which is diagrammatically indicated.

Fig. II is a view similar to the preceding figure with the container seated and the lifting sling being lowered over the same.

Fig. III is an end view of the lifting sling; and, Fig. IV is a plan view of the lifting sling.

As an example of the application of a lifting sling of my invention to container transfer apparatus, there is shown in the drawings a rigid overhead beam 35 overhanging a railway track 3. On the railway track 3, a car 4 is represented with

a container 5 raised thereabove. The container 5 is provided at its four top corners with outwardly directed lifting hooks 36 and with inclined guide surfaces 34 leading to the lifting hooks.

The beams 35 are spaced in parallel relation at a distance apart corresponding substantially to the center to center distance between the pair of lifting hooks 36 at each side of the container 5. Supported on the base flange of each beam 35 there is a trolley 37. The two trolleys 37 are interconnected by a tubular casing 38 which houses at each end 39 suitable hoisting gear for elevating containers. The hoisting gear at one end is connected to the hoisting gear at the other end by a shaft which extends through the tubular casing 38. To operate the hoisting gear, there is provided an external sheave 40 with an operating chain 41 hanging down therefrom to within reach of a man standing alongside the container.

The lifting coupler is comprehensively designated at 2 and is suspended from the hoisting apparatus by means of chains 46. The lifting coupler is characterized by a pair of stirrup suspension arms 42, 43 pivotally connected at their ends by a shaft 44 and maintained in angular spread position with capacity for limited relative movement. The shaft 44 passes through and is supported at its end by spaced yokes 45 which are linked to the hoisting chains 46, one to each hoist. The stirrup suspension arms 42, 43 are of substantially U-shaped formation and their ends are accommodated within the yokes 45. Associated with each stirrup arm 42, 43 there is an operating rod 42a, 43a, constituting an extension of one end of the arm, each operating rod 42a, 43a, being on the opposite side of the shaft 44 from the suspension arm 42, 43 of which it is a part. The outer hook engaging portion or heel 47 of each suspension arm 42, 43 includes a straight bar which is adapted to engage a pair of hooks on one side of the container 5. At the end of each operating rod 42a, 43a, there is an eye 48 through which passes a control line 49, in the form of a flexible cable. Each control line 49 passes through the eye 48 of one operating rod 42a, 43a, and leads to the heel 47 of the other suspension arm. Stops 50 in the control lines 49, of a size too large to pass through the eyes 48, hold the suspension arms 42, 43 in spread position when they are not engaged with the container. At their ends the control lines 49 terminate in weighted handles 51 which extend downwardly within the reach of a man standing alongside the container 5. The stops

50 serve to limit the closure of the suspension arms 42, 43.

In the event that it is desired to remove a container 5 from the railway car 4, the operation of the above described apparatus is as follows: The lifting sling 2 is positioned immediately over the container to be engaged. The operator standing besides the car 4, or on its platform, manipulates the control line 49 to spread 10 the arms 42, 43 preparatory to engaging the hooks 36 on the container. With the suspension arms 42, 43 spread apart to the position shown in Fig. II, the sling is lowered by operation of the hand chain 41 of the hoisting mechanism 15 to the point where the heels 47 of the arms 42, 43 contact with the guide surfaces 34 at the top of the container adjacent to the hooks 36. Conveniently, the operator accomplishes the above movements by holding the handle 51 of the control line 49 with one hand, while working the hand chain 41 of the hoisting apparatus with the other hand. After the lifting sling 2 has 20 been thus lowered to the top of the container, the operator releases his grip upon the handle 51. Incident to the hoisting of the lifting sling, the 25 heels 47 of the arms 42, 43 will be guided into the bights of the hooks 36 and the coupling will be completed in the manner shown in Fig. I.

In uncoupling the lifting sling 2 from a container, the operation is as follows: When the container is lowered by the hoisting apparatus to the platform to which it has been transferred, the operator continues to pay out the chains 46 of the hoisting apparatus until the lifting sling, 30 under the influence of its own weight, is caused to spread its arms 42, 43 clear of the hooks 36 of the container. With this accomplished, the handle 51 of the control line 49 is grasped, and the arms are thus held in spread position while 35 the operator, with the other hand, manipulates the hand chain 41 of the hoisting mechanism to raise the lifting sling.

While I have chosen to describe my invention in its application to containers having lifting hooks attached to the top thereof, the invention 40 is also useful where the lifting sling and the containers are provided with other forms of mutual engaging devices. Moreover, though in the preferred embodiment of my invention I employ 45 two operating rods 42a, 43a and control lines 49 depending at each side of the container, it will be apparent that the use of one operating rod and one control line is also contemplated.

While my invention has been described in 50 some detail with reference to one example of the practice thereof, it will be apparent that

various changes may be made in the form of the apparatus without departing from the spirit of the invention as defined in the annexed claims.

Having thus described my invention, I claim:

1. A lifting sling for containers comprising stirrup suspension arms pivotally connected to each other at their ends and maintained in angular spread position with capacity for limited relative movement, an extension rod leading from the end of one such arm to a point above the heel of the other arm, and means for controlling the spread of said arms in the form of a flexible cable extending upward over the end of the extension rod and downward to the heel of the adjacent arm and fastened thereto. 80

2. A lifting sling for containers comprising spaced yokes suspended from a hoisting apparatus, a shaft supported by said yokes, U-shaped suspension arms having their ends pivotally connected to said shaft within said yokes, and maintained in angular spread position with capacity for limited relative movement, an extension rod leading from the end of one such arm to a point above the heel of the other arm, and means for controlling the spread of said arms in the form of a flexible cable extending upward over the end of the extension rod and downward to the heel of the adjacent arm and fastened thereto. 85

3. A lifting sling for containers comprising stirrup suspension arms pivotally connected to each other at their ends and maintained in angular spread position with capacity for limited relative movement, an extension rod leading from the end of each such arm to a point above the heel of the other arm, and means for controlling the spread of said arms in the form of flexible cables, each extending upward over the end of one of said extension rods and downward to the heel of the adjacent arm and fastened thereto. 90

4. A lifting sling for containers comprising stirrup suspension arms pivotally connected to each other at their ends and maintained in angular spread position with capacity for limited relative movement, an extension rod leading from the end of one such arm to a point above the heel of the other arm, and means for controlling the spread of said arms in the form of a flexible cable extending upward over the end of the extension rod and downward to the heel of the adjacent arm and fastened thereto. 95

5. A lifting sling for containers comprising stirrup suspension arms pivotally connected to each other at their ends and maintained in angular spread position with capacity for limited relative movement, an extension rod leading from the end of each such arm to a point above the heel of the other arm, and means for controlling the spread of said arms in the form of flexible cables, each extending upward over the end of one of said extension rods and downward to the heel of the adjacent arm and fastened thereto. 100

6. A lifting sling for containers comprising stirrup suspension arms pivotally connected to each other at their ends and maintained in angular spread position with capacity for limited relative movement, an extension rod leading from the end of one such arm to a point above the heel of the other arm, means for controlling the spread of said arms in the form of a flexible cable extending upward over the end of the extension rod and downward to the heel of the adjacent arm and fastened thereto, and a stop attached to said cable and adapted to engage the extension rod to limit the closure of said suspension arms. 105

FREDERICK K. FILDES.

130

7. A lifting sling for containers comprising stirrup suspension arms pivotally connected to each other at their ends and maintained in angular spread position with capacity for limited relative movement, an extension rod leading from the end of each such arm to a point above the heel of the other arm, means for controlling the spread of said arms in the form of flexible cables, each extending upward over the end of one of said extension rods and downward to the heel of the adjacent arm and fastened thereto. 135

8. A lifting sling for containers comprising stirrup suspension arms pivotally connected to each other at their ends and maintained in angular spread position with capacity for limited relative movement, an extension rod leading from the end of one such arm to a point above the heel of the other arm, means for controlling the spread of said arms in the form of flexible cables, each extending upward over the end of one of said extension rods and downward to the heel of the adjacent arm and fastened thereto. 140

9. A lifting sling for containers comprising stirrup suspension arms pivotally connected to each other at their ends and maintained in angular spread position with capacity for limited relative movement, an extension rod leading from the end of each such arm to a point above the heel of the other arm, means for controlling the spread of said arms in the form of flexible cables, each extending upward over the end of one of said extension rods and downward to the heel of the adjacent arm and fastened thereto. 145

10. A lifting sling for containers comprising stirrup suspension arms pivotally connected to each other at their ends and maintained in angular spread position with capacity for limited relative movement, an extension rod leading from the end of one such arm to a point above the heel of the other arm, means for controlling the spread of said arms in the form of flexible cables, each extending upward over the end of one of said extension rods and downward to the heel of the adjacent arm and fastened thereto. 150
